UNITED STATES PATENT OFFICE.

HENRY O. HANNA, OF OAKLAND, CALIFORNIA.

VERTEGRAPH.

1,271,461.

Specification of Letters Patent.

Patented July 2, 1918.

Application filed March 20, 1917. Serial No. 156,202.

To all whom it may concern:

Be it known that I, HENRY O. HANNA, a citizen of the United States, residing at Oakland, in the county of Alameda, State 5 of California, have invented a new and useful Verteograph, of which the following is a specification in such full and clear terms as will enable those skilled in the art to construct and use the same.

10 This invention relates to a vertegraph or machine for producing a graph of the bony structures of the body.

It will be understood by those skilled in the art that the position the bones of the 15 back occupy with respect to each other determines certain pathological conditions of the system, and physicians make use of this fact in correcting such conditions by pressure or percussion upon the mal-aligned 20 bones.

This apparatus is intended to provide a record of the condition of the bones of the back whereby the patient may himself observe the position of the mal-aligned bones, 25 one graph showing the adjustment in one plane while the other graph will show the lateral mal-alignments.

Another object of the invention is to provide means whereby the apparatus may be 30 adjusted for persons of greater or less size as may be convenient, the tracing apparatus normally operating in a given position.

Another object of the invention is to provide a tracing board for the support of the 35 paper upon which the tracing is made which may be turned 90 degrees thereby producing on the same sheet of paper two tracings, one of which will show lateral mal-alignments and the other posterior or anterior mal- 40 alignments of the bones.

It will of course be clear that any animal might have the position of its bones delineated with this machine, although the apparatus is more especially adapted for 45 use with the human body, and is capable of producing a graph thereof in any position the body may assume.

Other objects of the invention will appear as the description proceeds.

50 An embodiment of the invention is shown in the drawings in which the same reference numeral is applied to the same portion throughout, but I am aware that there may be many modifications thereof.

55 Figure 1 is a side elevation of the complete apparatus,

Fig. 2 is a plan view of the complete apparatus,

Fig. 3 is an end elevation of the complete 60 apparatus.

Fig. 4 is a detail view of one of the table legs showing the slot through which the operating frame is raised and lowered, there being one of said slots in each of the table 65 legs,

Fig. 5 is an end view of the table showing the means for raising and lowering the table, and also showing the means for making the diagram with the sheet to be marked held in a vertical position, a portion of the 70 frame being broken away,

Fig. 6 is a view in elevation of the marker used for showing lateral deviations when the paper to be marked is held in the horizontal position, and

75 Fig. 7 is a view of the marking apparatus shown in Fig. 6, looking from the right Fig. 6.

The apparatus comprises a table having four legs 1, 2, 3 and 4, which legs are suitably connected with cross pieces 5 and side pieces 6 and 7, the top 8 being placed thereon to receive the patient. The legs 1 to 4 inclusive are hollow to receive posts, 9 to 12 inclusive, of the frame which supports the 80 tracing apparatus. Each of the posts 9 to 12 inclusive has a link 13 at its lower end pivotally connected thereto and connected with levers 14 or 15 as the case may be, there being two of said levers at each end of 90 the table. Each of the levers rests upon a pin 16 carried by a bracket 17 supported by the transverse end members 5, which hold the legs together. The two levers 14 and 15 are pivotally connected together at one end, 95 and are connected with a vertically extending notched plate 18, the object being to provide means whereby the posts 9 to 12 and rectangular frame 13' carried at the top of said post may be adjusted in height, 100 the notches in the plate 18 engaging a screw or bolt 19 to hold said posts and the frame connected therewith at different levels.

When the frame and tracing apparatus carried thereby has been moved to the desired 105 level, it is secured in that position by means of the set screws 17, 18, 19 and 20. The frame at the top of the posts 9 to 12 inclusive comprises two cross bars 13, and two longitudinal bars 20' and 21 connecting the 110 two bars 13. Depending from the longitudinal extending bars are two arms 23 and

24 at each side of the frame, and said arms form a support for a rod 25 at each side of the frame, which rod extends from one end to the other thereof, and which are connected with the end posts by means of screws 26 and 27. Each of the rods 25 is provided with a tubular slide 28, and said tubular slides are connected by means of two transversely extending rods 29 and 30. The rod 30 is provided with a Y shaped yoke having two arms 31 and 32 at the ends of which are slides 33 and 34, which are freely movable on the rod 30. The rod 29 has a slide 35 freely movable thereon, which slide is connected by means of a spiral spring 36 with the free end of the yoke. At the lower end of the yoke there is pivotally mounted an arm 37 which has a small ball 38 on its lower end to move along the object to be copied, and in order to set the arm 37 at the most convenient position for use a screw 39 is provided, said screw enabling the arm 37 to be adjusted with respect to the yoke which supports it, said yoke having two projecting lugs 40 and 41 at its lower end for the support of the pivot pin 42 carrying the arm 37. At the lower end of the yoke there is a rigid tubular arm 43, within which slides a rod 44 connected at its outer end to a tubular sleeve 45. A spring 46 surrounds the rod 44 and tends to hold the sleeve 45 upright. A rod 47 is rigidly connected with the sleeve 45 and pivotally connected at 48 with the yoke lug 41. A rod 49 is also loosely connected with the sleeve 55 and loosely connected with a ring 50 on the sleeve 35. A rod 52 passes loosely through the sleeve 45 and it has a pencil or stylus 53 at its lower end, said rod also passing through sleeves 54 and 55, the former connected with a weight 56 and the latter at the top of a cross arm 57 carried by the rod 58 extending upwardly from the weight 56. The cross arm 57 carries loosely an arm 59 which has a small weight 60 at one end thereof and which arm bears upon the top of the rod 52, the object being to hold the pencil 53 in contact with the paper on the board 62. The board 62 is pivotally mounted on bolts 63 and 64 which pass through the end posts 9 and 12, jointed links 65, 66, 67 and 68 holding the board when in the horizontal position shown in Fig. 3. The spring 36 tends to hold the yoke arms up off the body on the table 8 while a spring 69 tends to pull slides 28 to the left hand end of the machine, see Fig. 1; the object being to reduce the pressure required to push the slides along when the apparatus is in use.

60 The operation of the apparatus just described is as follows:—Assuming a person to lie upon the table in the position shown in Fig. 1, the pointer 38 is moved along the median line of the back bone, and as the pointer moves along, the slides 28 will move

along their supports and the weight 56 and pencil 53 will be moved along the board 62 and in the position shown in Fig. 1. The resulting graph will delineate the position occupied by the several vertebrae of the spine, with respect to lateral planes.

When it is desired to take a graph of the interior or posterior positions of the several bones of the spine, the table 62 is turned up to the position in which it is shown in Fig. 5, the rod 47 is disengaged from the rod 44 and is raised up to the dotted position shown at 47', the rod 49 is disengaged from the pencil carrying sleeve 55 and the pin 44' is removed from the end of the rod 44 and tube 43 in which it is slidable thereby allowing the rod 44 to move longitudinally under the action of the spiral spring surrounding it. The rod 44 then has a pencil applied at its end, and as said pencil is moved along the paper fastened on the board 62 it makes a mark which corresponds to the several positions of the back bone processes in a plane at right angles to the plane of the mark previously made.

In order to make it possible to take the contour of a body with the person standing, the table and frame is intended to be tipped up to a vertical position so that it will then rest on the floor with the left hand end of the table, and the legs L, L' on the floor. This makes it possible to take a graph of a person in the normal standing position, the mal-alignments in both planes being equally well taken.

Having thus described my invention, what I claim as new and desire to secure by Letters Patent of the United States, is as follows, express reservation being made of permissible modifications.

1. An apparatus for producing graphs comprising a table, an adjustable frame supported thereby, a pivoted drawing board carried by said frame capable of being moved into two planes at right angles to each other, and a parallel motion apparatus carried by the frame for delineating upon the drawing board or paper thereon graphs corresponding to the shape in two planes of an object placed upon said table.

2. An apparatus for producing graphs comprising a table, a vertically adjustable frame supported thereby, a pivoted drawing board carried by said frame capable of being moved into two planes at right angles to each other, and a parallel motion apparatus carried by the frame for delineating upon the drawing board or paper thereon graphs corresponding to the shape in two planes of an object placed upon said table.

3. An apparatus for producing graphs comprising a table, an adjustable frame carried thereby, a pivoted drawing board capable of being moved into two planes at right angles to each other at the side of the frame,

longitudinally extending rods carried by said frame and a parallel motion apparatus 5 slideable on said rods and adapted to delineate upon the drawing board or paper thereon the shape of objects placed upon the table.

4. An apparatus for producing graphs comprising a table, an adjustable frame supported thereby, a pivoted drawing board at 10 the side of the frame capable of being moved into two positions at right angles to each other, longitudinally extending rods carried by said frame, slides on said rods, transversely extending rods connecting the 15 slides and suitable parallel motion apparatus slidably supported upon the latter rods and adapted to produce a graph upon the drawing board or paper thereon of objects placed upon the table.
5. An apparatus for producing graphs comprising a table, a frame supported thereby, a drawing board pivotally mounted upon one side of the table and adapted to be moved into a horizontal or a vertical 20 plane, a tracer movable in contact with the drawing board and suitable parallel motion apparatus for causing said tracer to delineate upon the drawing board or paper thereon the configuration of an object 25 placed upon the table.
6. An apparatus for producing graphs comprising a table, an adjustable frame carried thereby, a drawing board on the said frame capable of being moved to a horizontal or a vertical position, a tracer movable 30

over the drawing board, a suitable parallel motion apparatus connected with said tracer for moving it, and an adjustable pointer arm carried by the parallel motion apparatus for tracing the contour of an object 40 whereby a graph thereof is produced upon the drawing board or paper thereon.

7. An apparatus for producing graphs comprising a table, a vertically adjustable frame carried thereby, a drawing board pivotally mounted on the frame to be moved to a vertical or a horizontal position, a tracing point movable along the drawing board, a laterally and longitudinally slideable parallel motion apparatus adapted to pass over 45 objects on the table, and connections between the latter apparatus and the tracer whereby a graph of the object on the table may be produced on the drawing board.

8. An apparatus for producing graphs comprising a table, a frame adjustable with respect to the table, a drawing board movable into a horizontal or a vertical plane, a tracer movable along the drawing board, a parallel motion apparatus connected with 50 the tracer and having a guide for causing the tracer to move parallel to the guide in one plane, and a spring to return the parallel motion apparatus to one end of the frame after having been moved to the other 55 end thereof.

In testimony whereof I have hereunto set my hand this 13th day of March, A. D. 1917.

HENRY O. HANNA.
